UNITED STATES PATENT OFFICE.

HARRY E. SOREF, OF MILWAUKEE, WISCONSIN, ASSIGNOR TO MASTER LOCK COMPANY, OF MILWAUKEE, WISCONSIN, A CORPORATION OF WISCONSIN.

DESIGN FOR A LOCK CASING.

Application filed May 7, 1928. Serial No. 26,597. Term of patent 14 years.

To all whom it may concern:

Be it known that I, HARRY E. SOREF, a citizen of the United States, and a resident of the city of Milwaukee, in the county of Milwaukee and State of Wisconsin, have invented a new, original, and ornamental Design for Lock Casings, of which the following is a specification, reference being had to the accompanying drawing, forming a part hereof.

In the drawing, Figure 1 is a perspective

view showing my new design of lock casing, and Fig. 2 is a bottom plan view thereof.

I claim:

The ornamental design for a lock casing, as shown.

In testimony whereof, I have signed my name at Milwaukee, this 28th day of April, 1928.

HARRY E. SOREF.
